CUTLERY HANDLE

Albert W. Krock, Fremont, Ohio, assignor to
The Scott & Fetzer Company

Filed Sept. 20, 1971, Ser. No. 182,297

Term of patent 14 years

Int. Cl. D7—03

U.S. Cl. D95—3

FIG. 1 is a perspective view of a cutlery handle showing my new design.

FIG. 2 is a top plan view.

FIG. 3 is a side elevational view of one side.

FIG. 4 is an end elevational view as seen from the left of FIG. 3.

FIG. 5 is a side elevational view of the other side.

FIG. 6 is an end elevational view as seen from the right of FIG. 3.

FIG. 7 is a cross-sectional view taken along reference view lines 7—7 of FIG. 3.

I claim:

The ornamental design for a cutlery handle, as shown.
